US0D1026310S

(12) **United States Design Patent** (10) **Patent No.:** **US D1,026,310 S**
(45) **Date of Patent:** **** May 7, 2024**

(54) **HAIR DRYER**

(71) Applicant: **Dyson Technology Limited**, Wiltshire (GB)

(72) Inventors: **Peter David Gammack**, Gloucester (GB); **Stephen Benjamin Courtney**, Gloucester (GB); **Clément Bernard Christmann**, Schiltigheim (FR); **Wee Guan Tan**, Singapore (SG); **Bun Tiong Chua**, Kulaijaya (MY); **Min Yu Nicole Chian**, Singapore (SG); **Paul Thomas Brittell**, Bolton (GB); **Be Seng Lok**, Singapore (SG)

(73) Assignee: **Dyson Technology Limited**, Wiltshire (GB)

(**) Term: **15 Years**

(21) Appl. No.: **29/806,145**

(22) Filed: **Sep. 1, 2021**

(30) **Foreign Application Priority Data**

(57) **CLAIM**

The ornamental design for a hair dryer, as shown and described.

DESCRIPTION

FIG. 1 is a perspective view of a hair dryer, illustrating our new design;

FIG. 2 is an enlarged top view thereof;

FIG. 3 is a rear view thereof;

FIG. 4 is a right side view thereof;

FIG. 5 is an enlarged bottom view thereof;

FIG. 6 is a left side view thereof; and,

FIG. 7 is a front view thereof.

The broken lines depict portions of the hair dryer that form no part of the claimed design.

1 Claim, 7 Drawing Sheets
